[57] CLAIM

The ornamental design for a tape measure, as shown and described.

DESCRIPTION

FIG. 1 is a fragmentary top plan view of a tape measure showing my new design;

FIG. 2 is a fragmentary front elevation thereof; the rear elevation being a mirror image thereof;

FIG. 3 is a fragmentary bottom plan view thereof;

FIG. 4 is a right side elevation thereof; and,

FIG. 5 is a left side elevation thereof.

Portions of the tape measure have been omitted for ease of illustration.

FIG. 1

FIG. 2

FIG. 3

FIG. 4

FIG. 5
